UNITED STATES PATENT OFFICE.

WILLIAM F. WREN, OF SPOKANE, WASHINGTON.

FOUNTAIN SHAVING-BRUSH.

1,275,516.

Specification of Letters Patent. Patented Aug. 13, 1918.

Application filed July 25, 1917. Serial No. 182,687.

To all whom it may concern:

Be it known that I, WILLIAM F. WREN, a citizen of the United States, residing at Spokane, in the county of Spokane and

5 State of Washington, have invented new and useful Improvements in Fountain Shaving-Brushes, of which the following is a specification.

This invention relates to improvements in 10 fountain brushes and has to do more particularly with improvements in shaving brushes wherein the soap to form the lather is supplied to the interior of the brush.

One of the objects of my invention is to 15 provide a shaving brush especially equipped to coact with an original package of manufacture, in dispensing the soap or other contents of the package into the brush. Thus the brush would be especially made for use 20 in connection with a specific and original article of manufacture, and vice versa.

My invention includes a hollow handle adapted to receive a tube of shaving paste or soap, and the handle is equipped with a 25 brush discharge spout which is arranged for connection with the discharge opening of the tube so that the tube will discharge directly into said spout. The original package contains a follower which is adapted to co- 30 act with manually operable means on the brush handle to advance the follower and force the contents of the tube through the spout and into the brush.

A further feature of novelty consists in 35 providing the spout with a closure which is adapted to be opened when the contents of the tube is forced through the spout, the valve closure being arranged in a manner to cause the bristles of the brush to seat the 40 closure when the brush is flexed by wiping engagement to the face. Thus if the contents of the tube is especially fluid, in consistency, the improved valve will prevent waste of the soap.

45 My invention includes the novel form of brush, and the novel form of the original package of manufacture, separately, and my invention also includes the two in combination.

50 Other features and objects of the inven-

tion will be more fully described in connection with the accompanying drawings and will be more particularly pointed out in and by the appended claims.

In the drawings:

Figure 1 is a view in elevation of my improved fountain shaving brush.

Fig. 2 is a vertical longitudinal sectional view thereof.

Fig. 3 is a view partly in elevation and 60 partly a section of the original package or tube detached from the brush.

Fig. 4 is a view in elevation of a portion of the follower actuating means.

Fig. 5 is an enlarged sectional view of the 65 discharge end of the paste tube.

Like characters of reference designate similar parts throughout the different figures of the drawings.

As shown, a handle structure is provided 70 which comprises a handle portion 1 and a brush portion 2. The brush portion 2 consists of a ferrule 3 to which the bristles or hairs of the brush 4, are secured. The ferrule 3 is exteriorly threaded at 5 and is provided with an end wall 6. A discharge tube 7 is connected at 8 to the end wall 6 and said discharge tube is shown interiorly threaded at its intake end. Slightly beyond its intake end, the discharge tube 7 is reduced at 9 and the same projects beyond the ferrule, or in other words the point of mount of the bristles, into the interior thereof. A valve closure 10 is adapted to seat against the terminal end of the tube and it will be noticed 85 that the closure 10 projects somewhat beyond said terminal end. Therefore when the hairs of the brush are bent or flexed as a result of wiping engagement in spreading the lather over the face, the brush hairs will engage the closure and seat the same to prevent an excess or wasteful amount of soap being delivered to the brush. This is especially important where the paste be-

comes warm and its consistency is more fluid 90 than would be the case in cold weather, for instance. This feature is also important when the soap or paste is initially made of a somewhat fluid consistency.

In order to render the closing action of 100

the closure more accurate, I may provide the latter with a stem 12, having guiding pins 13 which will hold the closure to a linear path of movement thereby always insuring a 5 tight seat of the closure against the terminal end of the discharge tube. In order to limit opening movement of the closure, I provide the stem 12 with a stop bar 14 which is adapted to engage the inner wall of the discharge tube at the point of reduction of the 10 latter.

The handle portion 1 comprises a hollow cylindrical body 15 which is threaded at its discharge end at 16 for detachable connection 15 with the ferrule 3. A cap 17 is provided for closing the remaining end of the handle 15. In accordance with this construction, the cap 17 is not threaded onto the handle portion 15 because the latter is usually 20 made of very thin material and it is desirable to have the interior of the handle of uniform internal diameter for a reason which will presently appear. Therefore I have provided a bayonet joint connection 25 consisting of a slot 18, formed in the cap, and a pin 19 mounted upon the handle 15. Thus in one direction, rotary thrust on the cap will not disengage the same from the handle.

30 It is one of the features of my invention to provide a shaving brush which is especially designed for coaction with an original package of manufacture, such for instance as a tube of shaving cream. I have 35 shown a tube in Fig. 3, as indicated at 19, the lower end being reduced at 20 to abut against a coacting reduction 21, of the handle 15, to limit insertion of the tube therein. The tube 19 is provided with the usual externally 40 threaded discharge end 22, which is closed by a cap 23. In the remaining end of the tube, after the contents 24 have been packed in, is a follower 25. This follower 25 is provided with an interiorly threaded and 45 centrally disposed hub 26. I may provide the follower 25 with a facing of thin rubber or like gasket 27, the peripheral margin 28 of which extends about the periphery of the follower to make a tight fit against 50 the inner wall of tube 19. A seal or cap 29 is placed over the end of the tube 19 when the tube is closed by the manufacturer to form the original package. Thus there 55 and the sealing means, the purpose of which will presently appear.

While my improved brush is not absolutely dependent for use in connection with this special type of original package, it will 60 now be clear that when this package is used, the tube will be inserted into the handle after the cap 23 has been removed, and when the ferrule 3 is threaded onto the handle 15 the threads of the discharge tube 7 65 will turn onto the exterior threads of the

discharge end 22 in such a manner as to secure the tube of paste in the handle. Of course it will be difficult to rotate the tube of paste in the handle to make this thread connection, although this might be possible 70 notwithstanding the fact that the tube is intended to fit rather snugly in the handle. It will be noted that removal of the ferrule 3 from the handle will greatly facilitate the operation of removing an empty tube and 75 therefore, in this combination, I consider it an important feature of the invention to provide a removable brush ferrule which is adapted, when applied to a handle, to make threaded connection with the handle, and 80 with an original package inside of the handle, simultaneously.

After the paste tube has been inserted into the handle, with the seal 29 previously removed, and all the parts being connected as 85 shown in Fig. 2, then the actuating mechanism which I am now about to describe will be applied.

This actuating mechanism comprises a threaded actuating member, preferably in 90 the form of a rod 30, which is of a length approximately equal to the length of the paste tube. The rod 30 is reduced at 31 to provide a shoulder 32, and the shoulder 32 abuts against the cap 17 so that the latter 95 will prevent longitudinal movement of the rod or spindle 30 in a direction outwardly from the handle. The rod 30 is rotatively mounted in the cap 17. An actuating member 33 shown in the form of a knurled disk 100 seats on the exterior of the cap 17 and is securely fixed to the reduced end 31, of the rod 30. Thus when the cap 17 is removed the rod and disk 30 and 33 will also be removed from the handle.

Assuming that the paste tube has been inserted into the handle with the cap 17 detached and the seal 29 removed, then the rod 30 will be turned into and through the follower and downwardly in the paste tube 110 until the cap 17 is in a position to be secured as shown in Fig. 2. The rod 30 will have a left hand thread so that by rotating the disk 33 to the right, the rod 30 will advance the follower downwardly in the paste tube from 115 the position shown in Fig. 3 to the position shown in Fig. 2, and so on, until the contents of the paste tube are used up.

It will now be clear that it is not necessary to transfer the shaving soap or paste 120 from the initial original package or tube to the handle, and this advantage not only renders the device more sanitary but it greatly facilitates the operation of using the paste. It will also be understood that a hollow 125 brush handle might become very unsanitary by reason of repeated use, whereas with the present device, the soap or paste is only in contact with the tin or lead of the original package. As regards the removable brush 130

portion, this can be easily cleaned at any time.

Furthermore, by placing the paste inside of the handle, it is never necessary to carry 5 the paste as a separate article and therefore the device of my invention is particularly convenient to travelers.

While I have herein shown and described one specific form of my invention, I do not 10 wish to be limited thereto except for such limitations as the claims may import.

I claim:

1. In a fountain shaving brush device, a hollow handle structure provided with a 15 lathering brush, said structure having a soap discharging tube delivering interiorly of said brush, and freely movable means normally unrestrained against opening or closing movement and actuated by flexure of the 20 bristles for closing the discharge end of said tube, substantially as described.

2. In a fountain shaving brush device, a hollow handle structure provided with a 25 lathering brush, said structure having a soap discharging tube delivering interiorly of said brush, means for forcing the soap contents from said structure through said tube into said brush, and freely movable means 30 actuated by lathering flexure of the brush for closing the discharge end of said tube, substantially as described.

3. In a fountain shaving brush device, a hollow handle structure provided with a 35 lathering brush, said structure having a soap discharging tube projecting interiorly of the brush and beyond the point of mount of the bristles of said brush, and a freely movable valve normally unrestrained against opening 40 or closing movement and adapted to seat against the discharge end of said tube and projecting into the path of the bristles, whereby lathering flexure of the bristles will seat said valve closure, substantially as described.

45 4. In a fountain shaving brush device, a hollow handle structure provided with a lathering brush, said structure having a soap discharging tube projecting interiorly of the brush and beyond the point of mount of the

bristles of said brush, a valve closure freely 50 movable longitudinally of said tube and seating against the end of said tube and projecting into the path of the bristles, whereby the valve closure will be seated when the bristles are flexed, and means for forcing 55 soap through said tube and opening said valve closure, substantially as described.

5. In a fountain shaving brush device, a hollow handle structure provided with a lathering brush, said structure having a soap 60 discharging tube projecting interiorly of the brush and beyond the point of mount of the bristles of said brush, a valve closure freely movable longitudinally of said tube and seating against the end of said tube and 65 projecting into the path of the bristles whereby flexure of the latter will seat said valve closure, said valve closure being provided with means for guiding the same interiorly of said tube to limit said closure to 70 a linear path of travel, substantially as described.

6. In a fountain shaving brush device, a hollow handle structure provided with a lathering brush and said structure having 75 a soap discharging tube terminating in a valve seat outlet located beyond the juncture of the bristles with the handle structure to lie within the flexing or bending zone of the bristles, a valve for engaging said seat 80 and projecting from the seat into the path of the bristles when the same are bent to thereby seat the valve, said valve having a stem of reduced size with respect to said tube and projecting therein whereby the soap 85 will flow through said tube along said stem, said stem having guiding portions engaging said tube on the interior thereof to hold the valve to a linear path of movement, and said stem also having a stop for limiting opening movement of said valve but said valve being otherwise free and unrestrained to move longitudinally of said tube, substantially 90 as described.

In testimony, that I claim the foregoing 95 as my own, I hereby affix my signature.

WILLIAM F. WREN.
